TENS-TRANSFER MECHANISM

Chi Liang Cho, Zurich, Switzerland, assignor to
 Electro-Watt Electrical and Industrial Management Co., Ltd., Zurich, Switzerland

Application January 11, 1949, Serial No. 70,337
 In Switzerland January 16, 1948

3 Claims. (Cl. 235—138)

1

This invention relates to a calculating device, in particular for cash registers, book-keeping and other calculating machines, having a full keyboard.

As is well known, in consequence of the manifold tasks which they have to undertake, cash registers and similar devices are particularly awkward and complicated in their construction, so that the possibility of acquiring them represents a considerable expense. Furthermore the capacity of the usual type of cash registers is not sufficient to satisfy all branches of the business in which they are used, since they can only furnish receipts or final amounts, most of the calculating work has therefore to be performed by the user of the register, who must thus treat detailed items separately, e. g. when adding them together and when making small multiplications, etc., in this there is constituted not only a source of error, but also a lack of thorough checking.

The object of the present invention is to provide a calculating registering device of the above mentioned type in which, on the one hand, calculations are centralised and simplified, so that the user can be freed entirely from mental calculation, and on the other hand the production capacity of the device is increased.

The present invention is essentially characterised in that the complete working operation for the setting, recording and printing of the numerals and also the indicating thereof is effected in each column of numerals by the direct action of a toothed rack, movable longitudinally in the machine, and of a system of bell-crank levers with staggered arms arranged transversely in the machine. The toothed racks are provided with a combination of contact teeth and contact steps. Each toothed rack cooperates on the one hand with its keys, and on the other hand, with various counting mechanisms in such a way that the toothed racks, before each calculating operation, are brought into the initial position by a member of the operating mechanism, and, during the forward movement of the member, are carried so far along by an operator until the corresponding tooth or step contact comes up against the foot of the corresponding depressed key. In this way, under the cooperation of the bell-crank arm appertaining to the toothed rack in question, a printing segment of the register is operated to record the operation on a suitable tape, whilst at the same time, by means of an appertaining articulated link-rod, at least one toothed segment is set into corresponding motion and is brought into mesh with at least one corresponding nu-

2

meral disc of an indicating mechanism. By bringing back the member of the operating mechanism into the initial position, all toothed racks, together with the printing segment, are again brought into the initial position. The depressed numerals are hereby transmitted to the various counting mechanisms and to the indicating mechanisms, after which the counting mechanisms opposite to the toothed racks and the toothed segment are disengaged from the indicating mechanisms, and, in the last phase, the operation of transmitting the tens in the various counting mechanisms is carried out by the action of shift levers with engaging rollers.

Further features of the invention will be apparent from the claims, specification and drawings, in which one form of device, according to the invention, as applied to a cash register, is illustrated purely as an example.

In the drawings:

Fig. 1 is a longitudinal sectional view of a portion of a calculating machine constructed in accordance with the present invention.

Fig. 2 is a perspective view of one of the detail-total counting shift levers.

Fig. 3 is a perspective view of an operating lever for the grand-total counting mechanism.

Fig. 4 is a detailed perspective view of a portion of Fig. 1.

In the construction shown on the drawings, the cover 1 of the machine and the bearing plate 2, lying parallel under it, are fixed to two transverse bars 12 and 13 which in turn are fixed to the two side walls of the machine; in the plate 2 and in the cover 1 all keys 4 are arranged so that they can be pressed down against the action of the spring 6 and work directly together with racks 20.

A rack 20 is provided for each column of numerals. Each rack is perforated by a slot 23 and is supported, on the one hand, on a member of the operating mechanism, i.e. on a transverse bar 58 passed through the slots 23, Fig. 2a, and, on the other hand, on two cross bars 26, 43, movable along the machine by means of the guiding combs 27, 42, respectively. On the upper edge of the racks, 20, are two systems of stops, one system being formed by projections 21 the other by steps 22. The racks are further provided at their lower edges with a series of teeth 24 engageable by a detail-total counting mechanism 17 and at the same time by several grand-total counting mechanisms 16. At its front end, each rack 20 is connected by means of rock shaft of the machine. In the lower edge of each slot 23 there is provided a small notch into which a

click roller 60 may enter upon which a spring, not shown in detail, rests, housed in a longitudinal groove 59 of click roller 60 designated as the "operator" in the description that follows.

For transmitting each of the set numeral values to the windows of the machine, not shown, for viewing by seller and buyer, a pair of indicating mechanisms, not shown, should be provided for each digit or other data to be shown and for each window. These indicating mechanisms are operated from the rock shaft through suitable lever arrangements, not shown.

The keys, supported in the cover 1 and in the bearing plate 2, consist, as Fig. 5 shows, of a head part 4 and a guiding part 5 with a foot 5b 15 and a groove, not shown, at a suitable location for taking the spring 6; they are provided also with a nose, not shown, acting as a stop against the bearing plate 2 and at the same time as a locking cam for the key-lock 8 when in the 20 pressed-down position. The foot lengths 5b of the keys 4 of the larger numerals (4 . . . 9) are also shaped in steps corresponding to the step-like contacts 22 on the racks 20, whilst the feet 25 of the keys of the smaller numerals (1 . . . 3) are all of the same length.

Beside each row of keys a key lock 8 is arranged, which is swingingly supported on the parallel stationary bars 12, 13 by means of two pins 9 and these locks are pressed by springs 15 30 pins 9 and these locks are pressed by springs 15 against noses, not shown, on the guiding parts 5 of the keys, so that locking takes place when the keys are depressed. The front part of each key-lock 8 is connected to still another locking arm 11, by means of which the racks 20 are firmly held in the initial position by means of their teeth 21. A recess under the nose of each of the guiding parts 5 of the keys is cut-in deeper than the upper part thereof. After depressing the keys 35 the key-lock 8 makes a small swing to the side, so that the racks 20 are freed from the locking arm 11.

The key spring 6 is interlaced in the form of a net under the cover 1 in grooves 14 of the rails 7, supported on the transverse bars 12, 13, the interlacing being such that the spring becomes placed diagonally between the neighbouring rails 7 at distances of two grooves from each other, it being possible to arrange the key guiding part 5 in the middle of the diagonals. The spring 6 consists of a closely wound coiled spring and is laid into the rail 7 either in one piece or in several pieces arranged in groups. The keys 4, 5 are pushed into the cover 1 direct from above; and by its springing action, the spring 6 is automatically inserted into the grooves of the key part 5, whereby the spring 6 acts at the same time as a stop against the cover 1, in order to hold the keys firmly in a raised position. The object of arranging the interlaced spring 6 diagonally is to obtain the greatest possible length of spring for each key.

Now with respect to the carrying-over of the tens, members for carrying over the tens are provided for the grand-total counting mechanism 16 and for the detail-total counting mechanism 17, Figs. 1 to 3. Both members are arranged to be commonly supported on one centralised bearing. They consist of two shift levers 37, 37a, which are pivotally supported beside each other on the shaft 38, and of two shift toothed racks 44, 44a for the detail total and the grand total and also of a common engaging roller 35 with the engaging teeth 34; the roller 35 is pivotally supported in the two side walls and is in connection with the

drive of the machine. The shift lever 37 (Figure 3) is bent U-shaped above and has an upper arm 39 with the engaging tip 40b and a lower arm with two engaging teeth 33, 36 and also a click cam 31. The shift lever 37a is shaped the same as the shift lever 37, except that instead of its U-shaped bearing, it has a bushing 38b with which the lever 37a is supported between the U-shaped bend of the shaft lever 37 on the common shaft 38. The shift racks 44, 44a are supported, each displaceable by one unit, in common on the cross bars 26, 43a and 47 by means of guiding combs 27, 46 and are provided on the upper edges with a row of teeth and on the lower edges with a nose 32, 32a bent downwards at right angles, and are secured by a click spring 25 in their proper position. For each column of numerals the engaging roller 35 is provided with two engaging teeth 34 for the shift levers 37, 37a, which teeth 34, in their order from the lowest to the highest numerals column, are arranged screw-like behind each other, and spaced at the same angle apart on the shaft 35, i. e. the tooth 34 corresponding to each numeral column stands opposite to the engaging tooth 36 of the corresponding shift lever 37.

The tens of the grand or detail totals are carried over as follows: For instance, as shown as the shift tooth 40 or 41 of the toothed wheels 16 or 17 of the grand or detail total mechanisms passes over from 9 to 10, the shift tooth comes up against the arm point 40b or 41b of the shift lever 37 or 37a of the next higher decimal place, whereby the upper arm 39 or 39a of the shift lever 37 or 37a is raised and swivels round the shaft 38 through a shift unit, the new position being maintained fixed by the spring 28 and the click cams 31, 31a and the shift tooth 33 of the shift lever 37 which stands in engagement with the bent nose 32 of the shift-tooth rack 44, Fig. 1. Both end phases of the calculating operation cause the machine to be advanced, after which the shift tooth 34 swings over the engaging tooth 36 of the shift lever 37 so that this lever is brought back into the initial position, whereby the shift toothed rack 44 is carried along through a shift unit since its nose 32 is in engagement and turns the respective counting wheel 16 or 17 also through one shift unit. In order to bring the shift toothed rack 44 back again into the initial position while the counting mechanism 16 or 17 is brought back out of engagement with the shift toothed rack 44 or 44a, its oppositely situated tooth bar 30, by rotating the main axle 18, is brought against the nose 29 of the shift toothed rack 44 or 44a and the shift toothed rack is thereby pushed back. The shift toothed racks 44, 44a lie underneath each other; rack 44a thus being concealed in Fig. 1 by rack 44; both racks 44 and 44a lie, however, parallel to each other, whereby those for the grand-total counting mechanism 16 lie in the same planes as the toothed racks 20, whilst the others of the detail-total counting mechanism are arranged displaced through a certain distance. The described system of carrying over the tens in accordance with the invention by pivoting shafts 55 situated beside each other has, in contrast to known systems, great advantages in that on the one hand it requires considerably fewer parts, but on the other hand works absolutely positively, i. e. has no movements produced by springs.

I claim:

1. In a calculating registering device, particularly for cash registers, book-keeping and other

calculating machines, having a full board of keys arranged in columns, with a slidably mounted rack beneath each column of keys, and mechanisms for grand total and detail total having their constituent parts moving adjacent one another; a pair of toothed shift racks for each of the slidably mounted racks, a pair of shift levers for each pair of shift racks and pivotally supported at one of their ends on a common axis, an engaging roller for each pair of shift levers, pins included in each of the mechanisms meshing with one of the shift racks of each pair and each having a shift tooth, each of said shift levers having an arm at its pivoted end to engage the shift tooth of the respective one of the pinions, each of said shift levers having two shift teeth at its end remote from its pivoted end, each of said shift racks having a nose projecting downwardly at right angles, one shift tooth of each of said shift levers being engaged by one of said noses, said engaging roller having engaging teeth, the other shift teeth of said shift levers being adapted to be engaged by the engaging teeth of said engaging roller, a click cam on each of said shift levers intermediate of their ends, a holding spring engaging each of said click cams, said engaging teeth of said engaging rollers being disposed so as to correspond to the sequence of columns of keys and arranged from the lowest up to the highest column of keys in a spiral line one behind the other with the same angular pitch, click springs holding the first-mentioned racks in initial positions, the first-mentioned racks being disposed in their initial positions out of engage-

5

ment with the pinions of said grand total and said detail total mechanisms, and slidably mounted bearing plates supporting said pinions and being movable to engage said pinions with the first-mentioned slidable racks, one shift rack of each pair of shift racks being in alignment with the respective slidably mounted rack and the other shift rack of each pair being disposed parallel to and to one side of the said one shift rack of each pair.

2. A calculating registering device according to claim 1, wherein the pinions of the grand total and the detail total mechanisms are supported in separate bearings on said bearing plates.

3. A calculating registering device according to claim 1, wherein each shift rack is provided with a toothed portion meshing only with the teeth of the pinion of its respective mechanism and with an untoothed portion aligned with the pinion of the other of the mechanisms.
